UNITED STATES PATENT OFFICE.

DWIGHT S. CLARK, OF CAMBRIDGEPORT, ASSIGNOR TO W. H. FORBES, OF BOSTON, MASSACHUSETTS.

INK-FOUNTAIN FOR PRINTING-PRESSES.

SPECIFICATION forming part of Letters Patent No. 375,126, dated December 20, 1887.

Application filed December 22, 1886. Serial No. 222,293. (No model.)

To all whom it may concern:

Be it known that I, DWIGHT S. CLARK, a citizen of the United States, residing at Cambridgeport, in the county of Middlesex and 5 State of Massachusetts, have invented certain new and useful Improvements in Ink-Fountains for Printing-Presses, of which the following is a specification.

This invention is related to a large number 10 of devices designed to effect and control the periodic supply of the ink or color used in printing-machines; and its special object is to facilitate the adjustment of the same and to hinder loss of material and time.

15 In the drawings forming part of this specification, Figure 1 represents the ink-fountain I have invented in plan. Fig. 2 is a back elevation of the same. Fig. 3 is a cross-section on the dotted line $x-x$. Fig. 4 is an end elevation of cam-rod; Fig. 5, a plan view of the same. Figs. 6 and 7 are side and end elevations, respectively, of the follower used in connection with the knife-adjusting screws; Fig. 8, a view of one of these screws.

25 In the figures, a represents the fountain-roll, which does not differ essentially from that in frequent use on large presses. The steel "knife" b is secured to the horizontal piece c , the ends of which are slotted so as to slide in and out 30 between the cheeks d , where they are held in proper position while in use by the screws e . The elastic knife-blade b is thereby maintained in its inclined position, so that its lower edge, when unconstrained, springs a short distance 35 away from the fountain-roll a , with which it is parallel. The ends or cheeks d , in which are the bearings for the roller-shaft f , are connected by the stiff girder g , and with it form the fountain-frame.

40 As in other fountains, the printing-ink is placed in the angular trough formed by the fountain-roll on one side and the knife on the other, and as the roll revolves it carries with it a film of ink upon its surface past the edge 45 of the knife. From this surface the doctor-roll, (not shown,) carries the requisite quantity of ink to the form-inking apparatus in the well-known manner. To govern the quantity of ink which shall adhere to the face of the 50 fountain-roll the knife in all fountains of this class is pressed with greater or less force

against said roll by means of set-screws similar to those shown at h , which pass through the frame and usually impinge against the plate near its lower edge. Screws of this kind 55 at short intervals asunder, and extending from end to end of the fountain, provide, also, the means for locally controlling the flow of ink, so that the same forms belts or rings upon the face of the fountain-roll, which vary in width 60 and thickness to suit the character of the work, and are in like condition transported to the inking apparatus by the action of the doctor-roll. This necessary adjustment of the ink, both general and local, is attempted in most 65 fountains; but it is invariably attended with difficulty and uncertainty, and it is the means for overcoming this difficulty which forms one part of the subject-matter of this invention. Furthermore, my invention consists in shutting off at any time the flow of ink totally by 70 a uniform and sufficient pressure of the knife against the face of the fountain-roll without thereby affecting the adjustment of the ink-supply when next the flow of ink is required. 75 Both these ends are secured by the devices now to be described.

The set-screws h , one of which is shown on a larger scale in Fig. 8, do not impinge upon the knife directly, as is usually the case, but 80 are adapted to push forward short intermediate rods, i , one of which is shown in side and end elevation in Figs. 6 and 7. It will be seen that each rod is provided with a squared head, which prevents it from turning, and that the 85 one-sided projection, formed as in the drawings, rests against one face of an angular groove in a cam-rod, k . When this rod is given the position seen in Fig. 3, the intermediate pieces, i , can all fall back as far as the set-screws h 90 will let them; but when the cam-rod is partially revolved in the direction of the arrow in Fig. 4, so as to strike the under side of the squared projection p on the intermediate pieces, the latter are all forced upward against 95 the knife and press it against the face of the fountain-roll.

In Fig. 4 an end elevation of the cam-rod is shown about full size, and in Fig. 5 a side elevation of part of it on a much smaller scale. 100 This rod is supported in the bearings l , and is also provided with the lugs m . The latter fall

into small recesses in the fountain-frame, where they act as levers whereby the cam-rod is given its partial revolution, the set-screws *n* being introduced through the heaviest part of the frame for that purpose. In lifting the intermediate rods, *i*, the projection marked *o*, Fig. 4, engages with the under side of the square head at *p*, Fig. 6, the flat planed upon the cam-rod (marked *q*) running its whole length, as indicated by the dotted line in Fig. 5.

One of the advantages secured by the interposition of the pieces *i* lies in the fact that they approach and press against the knife without turning, and as a consequence present always exactly the same part of the projecting end marked *r* to the plate, whereas when the screws *h* extend to the knife they are constantly rotated, and according to the pressure present a slightly varying spot on the end against the elastic steel blade. Such screws are in constant use, and the ends are subject to wear because of the rotation, which becomes in consequence somewhat one-sided in time; or they may have a slight eccentricity from the start. In either case a partial revolution of each screw does not give a proportionate result, and the pressman has in consequence to distrust the accomplishment of a desired change until he sees it. This is especially true when the set-screws *h* reach the knife obliquely and not at right angles, as in most of the drawings accompanying this specification. In many cases the position of the adjusting-screws which I have shown, though a very desirable one, is inadmissible because of the position necessarily given to the fountain in many presses.

In large power presses, and especially in those employed for chromatic printing, when the work ceases at the close of each day the set-screws in ordinary fountains should, as a rule, be tightened up to prevent dripping and waste. By doing this all the trouble of readjusting those screws has to be repeated each morning with much loss of time and waste. In the fountain I have invented, on the contrary, the screws *h* are not altered when the machine stops, only those marked *n* being screwed up, whereby the lugs *m* are acted upon and the cam-rod *k* made to turn, and so force at once all the intermediate pieces, *i*, up against the knife, and thereby cut off the flow of ink effectually. When the press is next started, the screws *n* are relaxed, and the intermediate pieces, *i*, falling back upon the ends of the screws *h*, the adjustment of the flow of ink is without more trouble exactly what it was

when the press stopped. The construction shown in Fig. 3 secures, moreover, the advantage that the points of contact used to force up the knife remain always the same, whether for the adjustment of the flow of ink while the press is running or for shutting it off completely without interfering with that adjustment when the work for a day ceases. Under these circumstances the strains to which the elastic plate is subjected are always alike in kind and in direction, which insures its uniform behavior indefinitely.

Having thus described my invention, what I claim, and desire to secure by Letters Patent, is—

1. In an ink-fountain, the combination of the fountain-roll and flexible knife with a series of screws for adjusting the edge of the knife in relation to the roll, and sliding followers having angular heads for preventing the turning of the same interposed between the screws and the knife, substantially as described.

2. In an ink-fountain, the interposed pieces *i* and the cam-rod *k*, engaged therewith, in combination with the screw *n* and with the fountain-knife, substantially as and for the purpose described.

3. In an ink-fountain, the combination of the fountain-roll and flexible knife with a series of set-screws for adjusting the edge of the knife in relation to the roll, sliding followers provided with heads interposed between the screws and the knife, and a cam acting upon the heads for forcing the edge of the knife against the roll, substantially as described.

4. In an ink-fountain, the combination of the fountain-roll and the flexible knife with a series of set-screws for adjusting the edge of the knife in relation to the roll, sliding followers interposed between the screws and the knife, and a lifting-cam acting upon the followers independently of the screws, substantially as described.

5. The combination, in an ink-fountain, of the roll *a*, the knife *b*, the intermediate pieces, *i*, provided with squared projecting heads *p*, the cam *k*, provided with the lugs *m* and actuated by the screws *n*, and the set-screws *h*, substantially as and for the purpose described.

In testimony whereof I have signed my name to this specification in the presence of two subscribing witnesses.
